UNITED STATES PATENT OFFICE.

ISAAC McDougall, SIDNEY McDougall, AND FRED HOWLES, OF MANCHESTER, ENGLAND.

MANUFACTURE OF TAR ACIDS.

1,077,287.

Specification of Letters Patent.

Patented Nov. 4, 1913.

Application filed June 6, 1913. Serial No. 772,211.

To all whom it may concern:

Be it known that we, ISAAC McDougall, SIDNEY McDougall, and FRED Howles, subjects of the King of Great Britain and Ireland, all residing at 66 and 68 Port street, Manchester, England, have invented certain new and useful Improvements in the Manufacture of Tar Acids, of which the following is a specification.

10 This invention relates to the manufacture or recovery of tar acids such as phenol, creosol and their higher homologues, and has for its object to provide an improved process for obtaining the said acids from tar distillates, 15 which is very efficient and economical to carry out. Heretofore various processes have been proposed for obtaining the said acids, the method at present employed consisting in the utilization of caustic soda for 20 separating the acids from the hydrocarbon oils in the tar distillate and the subsequent separation by chemical means of the acids from the caustic soda solution. Such process is expensive to carry out as it involves the 25 employment of a complicated plant and also the chemical separation and subsequent recovery of the caustic soda. There is also a considerable loss of the latter material during the carrying out of the process.

30 It is impossible to recover the tar acids alone by extraction by the use of the ordinary organic solvents for the latter dissolve not only the tar acids but also the hydrocarbon oils and produce a homogeneous mass.

35 By investigation and experiment we have found that the tar acids can be extracted from the tar distillate, comparatively free from hydrocarbon oils, by the utilization as 40 the extracting agent, of alcohol mixed with a suitable proportion of water. We find that good results are obtainable, when treating a high boiling point distillate, with from 23 to 25 per cent. of water added to commercial alcohol (i. e.—purified methylated spirits), and when treating a low boiling point distillate such as carbolic oil, with up to 40 per cent. of water added to commercial alcohol, but we do not limit ourselves to the 45 employment of such specific proportions as the latter may be varied to suit the nature of the product being treated. Excess of water prevents the separation of some of the tar acids while deficiency of water causes some of the oils to dissolve along with the acids. We may add two gallons of the

alcohol-water mixture to each gallon of tar distillate; or the alcohol-water mixture may be gradually added as extraction proceeds. We may, however, vary the above proportions.

50 By our process we obtain a fractional separation of the acids and hydrocarbon oils, the dissolved tar acids and hydrocarbon oils, owing to their different specific gravities, 55 can be drawn off from the receptacle or vessel in which the extraction has been accomplished, the alcohol being then recovered in the usual manner.

55 The extraction of, for example, blast furnace creosote oil, may be carried out as follows: Agitate one liter of creosote at ordinary atmospheric temperature with one liter of alcohol containing 27 per cent. of water: allow to settle; separate the partially spent 60 creosote from the acid extract; agitate the partially spent creosote with a further quantity of one-half liter of alcohol containing 27 per cent. of water: allow to settle and separate: the remaining partially spent creosote 65 may be again agitated with a further one-half liter of alcohol containing 27 per cent. of water. The last or third treatment practically completes the extraction of the phenoloids. Each extraction and separation 70 occupies about one hour. The extracts from each treatment are put together and distilled to recover the alcohol. The residue consisting of crude acids and water is allowed to stand until separation is complete. The 75 water which separates is added to the distilled alcohol. The acids are purified in the usual way by distillation. A small quantity of water first distills over and this is also added to the recovered alcohol. The distilled acids from this treatment measure 220, c. cs. The residual oil which contains about 80 15 per cent. of alcohol is heated until the alcohol is all distilled over when the residue measures 768 c. cs. The distillation is a simple process owing to the boiling points of alcohol and oil being so far apart. The remainder of the original liter of creosote consists of pitch. With ordinary care the total 85 loss of alcohol is under 1 per cent.

90 The accompanying diagram illustrates a plant suitable for use in carrying out our aforesaid process.

95 The vessel *a* contains alcohol mixed with the desired proportion of water having regard to the distillate to be treated. The latter is contained within the vessel *a* having an 100

105

110

agitator *c* of any convenient form arranged therein. The alcohol and water mixture is fed into the vessel *b* and is agitated along with the distillate. The tar acids separated from the distillate by the alcohol and water are led off into the vessel *d* while the hydro-carbon oils are passed into the vessel *e*. From the latter, the said oils are preferably returned two or more times to the vessel *b* by the pump represented by *f* so as to insure a high degree of efficiency in the extraction of the tar acids. A test cock is provided represented by *g*, to test the delivery from the vessel *b* so as to ascertain if tar acids or oils are passing therefrom. The flow to the vessels *d* or *e* is controlled accordingly.

The alcoholic extract (or tar acids, alcohol and water) is delivered by the pump *i* to the still *h* heated in a suitable manner, the alcoholic vapors given off passing through a condenser *j* on their way to the alcohol store *k*. The tar acids and water then pass to a separating vessel *m* where owing to their different specific gravities, the tar acids can be separately drawn off by the pump *n* and delivered to the acid still *o* and finally through the condenser *p* to the acid store *q*. After the acids, which are heavier than the water, have been drawn off, the water is drawn off by the same pump *n* and passed by way of the conduit *r* to the alcohol store *k* to provide a mixture of the strength originally determined. The hydrocarbon oils, after extraction is completed, are delivered by the vessel *e* to the oil still *s* suitably heated to vaporize any alcohol contained therein, the alcohol passing to the condenser *j* and store *k*. The oil is subsequently delivered from the still by means of a pump

t to a store tank—(not shown). Suitable control valves are provided for directing and regulating the flow of liquid between the various vessels: also pipes *u* for allowing of the free circulation of vapor between the vessels *a*, *b*, *d* and *e* as the said vessels are filled and emptied.

It will be understood that we do not limit ourselves to the form of plant described and illustrated but may modify the same to suit requirements. The illustration merely shows one arrangement of plant suitable for use in carrying out our process.

Having now described our invention what we claim as new and desire to secure by Letters Patent is:—

1. Process for the manufacture or recovery of tar acids from tar distillates, consisting in treating the latter with a mixture of alcohol and water, as set forth.
2. Process for the manufacture or recovery of tar acids from tar distillates consisting in agitating the latter with a mixture of alcohol and water, allowing the liquid to settle, and separating the partially spent distillate from the acid extract, the said process being repeated at least once, the extracted acid being subsequently distilled, as set forth.

In testimony whereof we have signed our names to this specification in the presence of two subscribing witnesses.

ISAAC McDougall.
SIDNEY McDougall.
FRED HOWLES.
